(57) **CLAIM**

The ornamental design for a foil roll unit for foil transfer unit, as shown and described.

DESCRIPTION

FIG. 1 is a front, right, top perspective view of a foil roll unit for foil transfer unit showing the new design;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a rear elevational view thereof;

FIG. 7 is a bottom plan view thereof; and,

FIG. 8 is a rear, left, bottom perspective view thereof.

The evenly spaced broken lines depict portions of the foil roll unit for foil transfer unit that form no part of the claimed design. The dot-dash broken lines depict a boundary of the claimed subject matter and form no part of the claimed design.

1 Claim, 7 Drawing Sheets
